UNITED STATES PATENT OFFICE.

JAMES S. CONANT, OF BOSTON, MASSACHUSETTS.

DESIGN FOR A CARD.

SPECIFICATION forming part of Design No. 28,375, dated March 15, 1898.

Application filed June 14, 1897. Serial No. 640,777. Term of patent 3½ years.

To all whom it may concern:

Be it known that I, JAMES S. CONANT, a citizen of the United States, residing at Boston, in the county of Suffolk and State of Massachusetts, have invented and produced a new and original Design for a Card, of which the following is a specification, reference being had to the accompanying drawing, forming a part thereof.

As shown in the drawing, the leading feature of my design consists in a piece of cardboard cut into a shape that represents in outline two shoes in elevation placed so that the backs are in contact, the border of the same being ornamented, as shown.

This design is particularly adapted for a business-card.

Having described my invention, what I claim as new, and desire to secure by Letters Patent, is—

The design for a business-card, as herein shown and described.

In testimony whereof I have signed my name to this specification, in the presence of two subscribing witnesses, on this 11th day of 25 June, A. D. 1897.

JAMES S. CONANT.
